UNITED STATES PATENT OFFICE

EARL R. SWANSON, OF CHICAGO, ILLINOIS, ASSIGNOR TO CHICAGO-CLEVELAND CAR ROOFING COMPANY, OF CHICAGO, ILLINOIS, A CORPORATION OF DELAWARE

RAILWAY CAR

Application filed April 4, 1930. Serial No. 441,562.

My invention relates to railway cars and more particularly to the end walls thereof made of one or more metallic plates or panels integrally formed with stiffening and reinforcing corrugations or embossments.

It is well known that the end walls of railway cars are subjected to forces of considerable magnitude due to inertia thrusts and pressures caused by shifting of lading within the car when the car is subjected to severe buffing and draft shocks. Although these thrusts may be more or less evenly distributed over the end wall as a whole, they are however frequently localized, thereby tending to distort the walls in relatively small areas. In order that the end walls may most efficiently withstand the thrusts or forces delivered thereto by the lading within the car the plate structure constituting an end wall is usually integrally provided with a plurality of strengthening and rigidifying corrugations which are however so formed and arranged that the structure will possess sufficient resiliency to prevent permanent distortion thereof.

The corrugations thus formed in the plates in effect constitute beams and in determining stresses therein they are considered as such. Heretofore in metallic end plates the corrugations have been so formed that they are substantially symmetrical, that is, the amount of metal disposed on one side of the neutral axis extending transversely of the corrugations is substantially equal to the amount of metal disposed on the opposite side of that axis. However, since practically all of the forces or thrusts to which the end wall of a car is subjected are delivered thereto from the interior of the car, the portion of the end wall adjacent the inside of the car is practically always in compression while the portion of the plate on the exterior of the car is practically always in tension. Due to these conditions, namely, that the portions of the plate between the neutral axis thereof and the inside of the car and the portions of the plate between the neutral axis and the outside of the car are respectively in compression and tension I have found that by positioning more metal in the extreme fibers of the cor-

rugations on the tension side of the plate than in the corresponding fibers of the corrugations on the compression side of the plate the plate possesses greatly improved characteristics as compared with end walls having symmetrically formed reinforcements. 55

The principal object of my invention is to provide the metal end plate of a railway car with a plurality of corrugations so formed and arranged that those normally in tension have a greater beam strength than those normally in compression. 60

Another object of the invention is to provide an end plate with a plurality of corrugations alternately projecting inwardly and outwardly with respect to the interior of the car on opposite sides of the neutral axis of the plate which extends transversely of the corrugations, the outwardly projecting corrugations being provided with reverse corrugations of less depth than the inwardly projecting ones. 65 70

A further object of the invention is to provide the corrugations normally in tension with a plurality of reverse corrugations of less depth and length than those normally in compression. 75

Other and more specific objects and features residing in advantageous forms, combinations and relations of parts will herein-after appear and be pointed out in the claims. 80

In the drawings illustrating preferred embodiments of the invention:

Figure 1 is an end elevational view of a railway box car having end plates constructed in accordance with the invention. 85

Figure 2 is a sectional view taken on line 2-2, Figure 1.

Figure 3 is a sectional view taken on line 3-3, Figure 1. 90

Figure 4 is a fragmentary enlarged sectional view taken on line 4-4, Figure 1.

Figures 5, 6, 7 and 8 are enlarged fragmentary sectional views taken on lines 5-5, 6-6, 7-7 and 8-8, respectively, of Figure 1. 95

Figure 9 is a fragmentary end elevational view of a railway box car showing a modified form of the invention.

Figure 10 is likewise a fragmentary end 100

elevational view of a railway box car showing still another modified form of the invention.

Referring more particularly to the drawings 1 indicates the roof of the car, 2 the end plate and 3 the end sill. As is usual the end plate is rigidly connected to the end sill 3 by corner posts 4 which, while they may be of any suitable form, have been depicted in the present embodiments of the invention as 10 of Z-shape. The end wall of the car consists of a plurality of metal plates 5 and a wooden lining 6, the latter being used to comply with the requirements of the American Railway Association. Although I have illustrated the 15 end wall as being made with two metal plates it will be readily appreciated that one or any number of these plates may be employed, the number solely depending upon the particular requirements of the railroads. If, as 20 shown in the drawings, two plates are used they may be connected in any convenient manner such as by rivets 7. The upper edge of top plate is preferably secured by rivets 8 to the end plate 2 while the lower edge of 25 the bottom plate is preferably secured by rivets 9 to the end sill 3. The marginal side edges of the plates may be conveniently flanged inwardly and rigidly connected to the corner posts 4. As the construction of 30 the two plates is the same in all major respects only one will be described.

The end plate is provided with a plurality of corrugations alternately projecting inwardly and outwardly with respect to the interior of the car on opposite sides of the neutral axis of the plate extending transversely of the corrugations. The position of this neutral axis has been indicated by the line 35 a—b in Figure 5 of the drawings. Since, as stated before, the thrusts or forces to which the end wall of the car is subjected are practically entirely delivered to it from the interior of the car, the outwardly projecting corrugations, designated by the reference numeral 10, may be considered as tension members of the end plate while the inwardly projecting corrugations, designated by the reference numeral 11, may be considered as compression members.

The outwardly projecting or tension corrugations 10 are so formed that they possess greater beam strength than the inwardly projecting or compression corrugations 11. While this may be accomplished by either 45 making the tension corrugations wider than the compression corrugations, the depth of the corrugations being substantially constant, or by making the tension corrugations deeper than the compression corrugations, the width 50 of the corrugations being constant, it is preferred to make the tension corrugations of greater depth and width than the compression corrugations. Although the corrugations have been illustrated as being substantially arcuate it will be appreciated that they

may be of any suitable or desirable contour.

All of the major corrugations extend substantially continuously from adjacent one edge of the sheet to adjacent the other edge thereof and they all preferably terminate 70 in substantially vertical lines. Each of the corrugations is of substantially uniform width between points slightly inwardly of its ends, these points being respectively designated by lines c—d and e—f on the two 75 lowermost corrugations in Figure 1. From these points to their ends the outwardly projecting or tension corrugations increase in width while the inwardly projecting or compression corrugations decrease in width. Although the compression corrugations are of 80 constant depth between the lines c—d and e—f, only the central portions of the tension corrugations are of constant depth, the extent of the constant depth portions of these 85 latter corrugations being defined by lines g—h and l—m. From these points the tension corrugations may advantageously decrease in depth substantially to their ends.

To further rigidify and strengthen the 90 plate each of the outwardly projecting tension corrugations 10 is preferably formed with a plurality of reverse corrugations 12. These reverse corrugations are located in the end portions of the tension corrugations and 95 since they extend inwardly to a less extent than the compression corrugations 11 they do not form a complete split in the tension corrugations. The reverse corrugations extend in the direction of length of the tension members, beginning at the points g—h and l—m where the latter start to decrease 100 in depth, and terminating at their outer ends in the vertical lines passing through the ends of the major corrugations. To compensate 105 for the reduction in depth of the tension corrugations the respective reverse corrugations progressively increase in depth and width to the points c—d and e—f as the former decrease in depth. Furthermore, since the tension corrugations increase in width from the points c—d and e—f respectively, to their 110 ends, the corresponding portions of the reverse corrugations decrease in depth and width. In this manner the excess metal which would 115 occur by variations in the dimensions of the major corrugations is taken up by the reverse corrugations. It will, of course, be appreciated that not only do the reverse corrugations take up the excess metal which 120 would otherwise result but they also stiffen the end portions of the tension corrugations, which are relatively large, thereby making them less resilient.

Although the invention has been illustrated as applied to a railway box car it will be readily apparent that it is not limited in its application to this type but may be applied with equal success to other cars, such as gondola cars. Furthermore the corruga- 125 130

tions need not be arranged horizontally as disclosed in Figures 1 to 8, inclusive, of the drawings but they may be arranged vertically as shown in Figure 9 or diagonally as shown in Figure 10.

5 The wooden lining 6 preferably contacts with the inner faces of the compression corrugations and may advantageously be secured to the end plates by nailing strips 13 interposed between the lining and the tension corrugations, being rigidly secured to the latter by any suitable means such as bolts 14.

From the foregoing it will be perceived that a car end so formed will efficiently withstand the thrusts to which it is subjected by lading shifting within the car.

I claim:

1. A railway car having an end plate provided with a plurality of corrugations, said corrugations alternately projecting inwardly and outwardly with respect to the interior of the car on opposite sides of the neutral axis of the plate which extends transversely of the corrugations, said outwardly projecting corrugations being of greater width than the inwardly projecting corrugations.

2. A railway car having an end plate provided with a plurality of corrugations, said corrugations alternately projecting inwardly and outwardly with respect to the interior of the car on opposite sides of the neutral axis of the plate which extends transversely of the corrugations, said outwardly projecting corrugations being of greater depth than the inwardly projecting corrugations.

3. A railway car having an end plate provided with a plurality of corrugations, said corrugations alternately projecting inwardly and outwardly with respect to the interior of the car on opposite sides of the neutral axis of the plate which extends transversely of the corrugations, said outwardly projecting corrugations being respectively of greater width and depth than the inwardly projecting corrugations.

4. A metallic plate for the end of a railway car having a plurality of corrugations alternately projecting on opposite sides of the neutral axis of the plate which extends transversely of the corrugations, the corrugations disposed on that side of the said neutral axis of the plate normally under tension being of greater width than the corrugations disposed on that side of the neutral axis of the plate normally under compression.

5. A metallic plate for the end of a railway car having a plurality of corrugations alternately projecting on opposite sides of the neutral axis of the plate which extends transversely of the corrugations, the corrugations disposed on that side of the neutral axis of the plate normally under tension being of greater depth than the corrugations

disposed on that side of the neutral axis of the plate normally under tension.

6. A metallic plate for the end of a railway car having a plurality of corrugations alternately projecting on opposite sides of the neutral axis of the plate which extends transversely of the corrugations, the corrugations disposed on that side of the said neutral axis of the plate normally under tension being respectively of greater width and depth than the corrugations disposed on that side of the neutral axis of the plate normally under compression.

7. A railway car having an end plate provided with a plurality of corrugations, said corrugations alternately projecting inwardly and outwardly with respect to the interior of the car on opposite sides of the neutral axis of the plate which extends transversely of the corrugations, said outwardly projecting corrugations being of greater beam strength than the inwardly projecting corrugations.

8. A railway car having an end plate provided with a plurality of corrugations, said corrugations alternately projecting inwardly and outwardly with respect to the interior of the car on opposite sides of the neutral axis of the plate which extends transversely of the corrugations, said outwardly projecting corrugations being of greater beam strength than the inwardly projecting corrugations and all of said corrugations extending substantially continuously from adjacent one edge of the plate to adjacent another edge thereof.

9. A railway car having an end plate provided with a plurality of corrugations, said corrugations alternately projecting inwardly and outwardly with respect to the interior of the car on opposite sides of the neutral axis of the plate which extends transversely of the corrugations, said outwardly projecting corrugations being respectively provided with reverse corrugations of less depth than said inwardly projecting corrugations.

10. A railway car having an end plate provided with a plurality of corrugations, said corrugations alternately projecting inwardly and outwardly with respect to the interior of the car on opposite sides of the neutral axis of the plate which extends transversely of the corrugations, each of said outwardly projecting corrugations being respectively provided with a plurality of reverse corrugations of less depth than said inwardly projecting corrugations.

11. A railway car having an end plate provided with a plurality of corrugations, said corrugations alternately projecting inwardly and outwardly with respect to the interior of the car on opposite sides of the neutral axis of the plate which extends transversely of the corrugations, each of said outwardly projecting corrugations being respectively pro-

vided with a plurality of reverse corrugations of less depth than said inwardly projecting corrugations, the outer ends of said reverse corrugations terminating substantially in line with the ends of said inwardly projecting corrugations.

12. A railway car having an end plate provided with a plurality of corrugations, said corrugations alternately projecting inwardly and outwardly with respect to the interior of the car on opposite sides of the neutral axis of the plate which extends transversely of the corrugations, the portions of the outwardly projecting corrugations between points respectively adjacent opposite edges of the sheet being of substantially uniform width, said portions of the corrugations being provided with reverse corrugations.

13. A railway car having an end plate provided with a plurality of corrugations, said corrugations alternately projecting inwardly and outwardly with respect to the interior of the car on opposite sides of the neutral axis of the plate which extends transversely of the corrugations, the portions of the outwardly projecting corrugations between points respectively adjacent opposite edges of the sheet being of substantially uniform width, said portions of the corrugations being provided with reverse corrugations of less depth than the inwardly projecting corrugations.

14. A railway car having an end plate provided with a plurality of corrugations, said corrugations alternately projecting inwardly and outwardly with respect to the interior of the car on opposite sides of the neutral axis of the plate which extends transversely of the corrugations, said outwardly projecting corrugations being of greater beam strength than the inwardly projecting corrugations, and said outwardly projecting corrugations being respectively provided with reverse corrugations of less depth than said inwardly projecting corrugations.

15. A railway car having an end plate provided with a plurality of corrugations alternately projecting inwardly and outwardly with respect to the interior of the car on opposite sides of the neutral axis of the plate which extends transversely of the corrugations, said outwardly projecting corrugations being of greater beam strength than the inwardly projecting corrugations and the portions of the outwardly projecting corrugations between points respectively adjacent opposite edges of the sheet being of substantially uniform width, said portions of the corrugations being provided with reverse corrugations.

In testimony whereof I affix my signature.
EARL R. SWANSON.
